UNITED STATES PATENT OFFICE.

JOHN T. BRODEN, OF SIOUX CITY, IOWA.

SIDING OR CLAPBOARD MARKER.

SPECIFICATION forming part of Letters Patent No. 412,594, dated October 8, 1889.

Application filed April 29, 1889. Serial No. 309,016. (No model.)

To all whom it may concern:

Be it known that I, JOHN T. BRODEN, a subject of the King of Sweden and Norway, and a resident of Sioux City, in the county of Woodbury and State of Iowa, have invented certain new and useful Improvements in Siding or Clapboard Markers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a perspective view. Fig. 2 is a section taken where the broken line $x x$ is marked on Fig. 3. Fig. 3 shows the marker with the cover removed, and a portion broken away. Fig. 4 is an end view.

This invention relates to markers to be used in fitting siding or clapboards to houses; and it consists in the construction and novel combination of parts, as hereinafter described, and pointed out in the claim.

The object of the invention is to provide a convenient tool which combines the qualities of compactness and strength for the use of carpenters, by means of which a siding or clapboard can be held horizontally in position against the side of a house and readily marked across as a guide for the saw in reducing the board to the required length to accurately fit in position.

In the accompanying drawings, the letter A designates a narrow rectangular metallic box or frame of suitable length, having a slotted bottom B and cover C.

B' is a metallic strip firmly secured to the bottom B of the box, and extended at each end thereof to form projections a a for the attachment of supporting-arms b b, which extend forward a suitable distance at right angles to the length of the box-frame to embrace between them the edges of the siding-board to hold the same in position when marking. The under surfaces of the arms b b are rabbeted, and through apertures rivets are passed, securing the arms respectively to the ends a of the strip B'.

Between the bottom of the box and the under surface of the arms b b and the strip B' is an intervening way or guide-slot for the reception of the marking-knife D. This marking-knife D is of elongated rectangular shape, and is serrated on its forward edge c to mark the board as a guide for sawing, and is provided with a handle or grip E at the back. The upper side of the knife is provided with upright lugs or posts e e, situated near each end thereof, which project through slots h h in the bottom B of the box. Each post e serves as a point of attachment inside the box for one end of a spiral spring i, the opposite end 65 of each spring being secured to a hook or loop k on the inside wall of the box. A semi-elliptic spring J is clipped inside the box opposite the spiral springs i i, and its free ends respectively bear under and against the uprights e. The object of the spring attachments is to steady the marking-knife to hold it in withdrawn position and regulate its action when in use. The marking-knife is centrally slotted at z for the passage of the middle securing-screw V, which holds the outer guide-plate B' to the bottom of the box. The motion of the knife given by means of its handle H is limited by the area of the slots h h and the lugs e e, which operate in said 70 slots.

When in practical use, the board-marker is applied and operated as follows: A clapboard, having been secured temporarily at one corner of the house in course of construction, is held against the corner or facing strip in the required horizontal position by means of the arms b b of the marker between which the board is placed. The outer flat sides of the arms are then made to bear against the inner 85 or meeting edge of the corner-strip, and the face of the box between the arms b b bears against the board to be marked, and thus brings the marking-knife in line with the perpendicular meeting edge of the corner-strip. 90 The marking-knife is then thrust forward against the board by means of the handle, and is given a vertical or up-and-down motion, which scratches the face of the board, forming a cross-marking at the front, where it is 95 designed to be sawed. The board is then removed to the carpenter's bench, the super-

fluous end sawed off at the mark, and is then ready to be nailed in position.

Having described this invention, what I claim, and desire to secure by Letters Patent, 5 is—

The siding or board marker consisting of the box frame or closure having at its ends arms standing at right angles to the length of said box-frame or closure, the marking-knife arranged in said closure and provided with a handle, said marking-blade having studs projecting through slots in said closure adapted to allow the marking-blade to have longitudinal and inward movement, the

springs connecting at their outer ends to said studs and having their inner ends connected about centrally to said closure, and the semi-elliptic spring centrally secured to said closure and bearing near its ends upon said studs, securing the marking-blade in a withdrawn 15 position, substantially as set forth.

In testimony whereof I affix my signature in presence of two witnesses.

JOHN T. BRODEN.
